APPLICATOR FOR DYES AND LOTIONS

Helen Pearson, Santa Ana, Calif.

Application May 9, 1949, Serial No. 92,165

4 Claims. (Cl. 132—12)

1

This invention relates to liquid applicators and more particularly relates to an applicator for applying dyes, lotions and similar liquids to the human hair.

With increased and more widely spread use of beauty treatments, not only do more women seek the aid of beauty parlors to improve their appearance, but an ever increasing number of women devote a large amount of time to home treatments, particularly with respect to treatment of their hair. Recent developments in home methods of waving the hair have increased this tendency, and have also increased the attendant difficulties and the necessity for caution and skill. Particularly in the application of dyes and of wave-setting lotions is it necessary to work with speed and with an even flow of liquid, in order that parts of the hair shall not dry prematurely or receive excessive or inadequate amounts of liquid. Furthermore, many of the liquids used for hair treatment are sufficiently caustic to burn the fingers. The skilled fingers of the beauty parlor operator have difficulty enough in manipulating the implements of the trade and the hair of the customer, and the woman who attempts treatment of her own hair has even more difficulty. The prevalent practice of using a tooth-brush and a bottle is dangerous, slow, and produces uneven results not enhancing to beauty.

It is accordingly an object of this invention to provide an applicator which is rapid and free-flowing and yet easily controlled as to quantity, and which is safe to handle.

A further object of the invention is to provide an applicator which combines in one instrument a reservoir for the liquid, a comb for separating and smoothing the hair, and a brush for applying liquid from the reservoir to the hair.

Still another object of the invention is to provide an applicator in which the flow of liquid is automatically cut off when the comb is in use, and in which reapplication of the brush, after a momentary use of the comb, causes the liquid to flow at full capacity.

Other objects and advantages of my invention will be specifically pointed out as the following description of preferred and modified embodiments of the invention proceeds, or will be apparent from consideration of the accompanying drawing, illustrative of said embodiments, in which:

Fig. 1 is a view in side elevation of a preferred form of applicator embodying the principles of my invention;

Fig. 2 is an end elevational view, taken from the left of Fig. 1;

2

Fig. 3 is a longitudinal sectional view, taken on the plane of section indicated by the line 3—3 of Fig. 1; and

Fig. 4 is a fragmentary plan view showing a modified form of the handle, or reservoir, end of the applicator.

Referring now to the details of the drawings, and having particular reference to the preferred embodiment illustrated in Figs. 1 to 3, my improved liquid applicator comprises a brush 6 carried by and in longitudinal extension of a generally cylindrical body portion 7 which forms a handle for manipulating the brush. The body portion 7 in turn comprises a tubular container 8 which is adapted to form a reservoir for liquids such as hair dyes or lotions, a stopper 9 for the container, a drip cup 10, and a comb 11 formed on the rim of the drip cup. The container 8 may suitably be of transparent plastic so that the color and the quantity of the liquid contained therein are readily apparent. Both for economy of manufacture and for uniform and pleasing appearance, the other members of the body 7 may also be of plastic, and I prefer to have these members, which include the stopper 9, drip cup 10, and comb 11, formed integrally as a unit. Obviously the stopper 9 could be separate from the drip cup 10, and the latter could be integral with the container 8, but as one of the objects of the invention is to obviate the need of touching the brush 6 when withdrawing the stopper from the container and to provide a handle by which the brush may be picked up when it is separated from the container, it is preferable that the stopper, drip cup and comb be separable from the container as a unit in which the brush is carried. Accordingly the bristles of the brush 6, which may also be of plastic, are mounted in the stopper 9, where they are protected except for their outer ends by the drip cup 10. The comb 11 thus serves as a handle for picking up the brush and stopper and as a lever for setting or loosening the stopper in the end of the container 8.

The stopper 9 forms the base of the drip cup 10, the latter being an outwardly flaring flange on the outer periphery of the stopper. Between the embedded clumps of bristles of the brush 6, the stopper 9 has a plurality of perforations 14, communicating between the container 8 and the base of the brush. The perforations 14 are preferably of small diameter, large enough to permit liquid to flow through freely when the difference of atmospheric and hydrostatic pressures at their ends permits such flow but not large enough to permit air bubbles to pass inwardly to the container 8 counter to an outward flow of liquid.

The size of the perforations 14 is therefore such that when the applicator is tilted so that liquid in the container 8 covers all the perforations in the stopper 9, liquid will flow outwardly through the perforations until creation of a partial vacuum within the container stops such outflow, and thereafter the applicator must be tilted in opposite inclination to uncover the perforations and to break the partial vacuum before outflow may resume.

To form the comb 11, a segment of the rim of the drip cup 10 is extended outwardly and inclined backward toward the container 8, its extended margin being there deeply serrated to form comb teeth 15. The angle between a line tangent to the comb teeth near their tips and the axis of the container 8 is less than ninety degrees, making it necessary to tilt the brush end of the applicator upwardly in order to point the comb teeth straight downwardly.

In the application of dyes and lotions to the hair, the dry, untreated hair is usually held gathered by one hand of the person applying the liquid while the applicator is held in the other hand. Locks of hair are successively separated by the comb from the dry side of a part in the hair and are then brushed with the brush to impart liquid to them. The action of first combing and then brushing the hair requires that the applicator be first tilted to a position in which the perforations 14 are uncovered by the liquid in the container 8 breaking any partial vacuum existing in the container, while the comb teeth 15 point downwardly toward the scalp, and then be tilted to a position in which the brush 6 is pointed toward the scalp and the liquid flows toward the brush end of the container and through the perforations 14. An excessive flow of liquid will soon be stopped by the creation of a partial vacuum in the container, and excessive liquid on the brush will be caught and returned towards the container by the drip cup 10 when the tilt of the applicator is reversed. The constant reversal of the tilt of the applicator prevents creation of such a partial vacuum that the brush will become dry.

In Fig. 4, I have illustrated a modification of my invention in which a comb 18 is disposed on the closed end of the container 8 with the comb teeth 19 pointed directly oppositely to the brush 6. The brush and the drip cup 10 (not shown in this view) may be the same as heretofore described, but the comb 11 may be omitted from the periphery of the drip cup, the comb 18 substituting therefor. It will be seen that this modified construction also necessitates reversal of the tilting of the applicator in order to point the brush and the comb 18 alternately toward the scalp.

Further modifications may be made in my applicator within the scope and spirit of my invention, which is not limited to the examples herein described and illustrated but is expressed in the appended claims.

I claim:

1. An applicator for applying liquids to the hair, comprising: an elongated container for said liquid, having an open end; a closure for said open end, having an opening for the escape of liquid from said container; a brush disposed to receive and to distribute liquid escaping through said opening and having its bristles aligned with the body of said container; and a comb having its teeth aligned transversely to the body of said container and directed rearwardly and divergently from the bristles of said brush by an angle exceeding ninety degrees.

2. An applicator for applying liquids to the hair, comprising: a container for said liquid, having an open end; a stopper for said open end, having perforations for the escape of liquid from said container, said perforations being substantially co-axial with said stopper; a brush set in said stopper co-axially with said perforations; a drip cup encircling said brush and integral with said stopper to form a handle therefor; and a comb having its teeth set at an obtuse angle to the normal direction of flow through said perforations so arranged that when the teeth of said comb are directed downwardly said perforations lead upwardly from said container.

3. In an applicator for applying liquids to the hair, comprising in combination an elongated handle including reservoir means, brush means on one end of said handle, passage means extending longitudinally of said applicator and communicating with said reservoir means and said brush means, and toothed means for parting the hair to permit close approach of said brush means to the roots of the hair, the improvement which consists in: disposing said toothed means with the teeth thereof directed in the longitudinal direction of said passage means away from said one end of said handle, whereby tilting said toothed means downwardly requires tilting upwardly said passage means from said reservoir means to said brush means.

4. In an applicator for applying liquids to the hair as described in claim 3, the improved construction set forth in claim 3 and a drip-cup on said handle encircling said brush means, said toothed means being disposed on the rim of said drip-cup.

HELEN PEARSON.
